UNITED STATES PATENT OFFICE.

JOSEPH H. COPE, OF DENVER, COLORADO.

SPRING-PULLBACK FOR HAYSTACKERS.

1,330,304.

Specification of Letters Patent. Patented Feb. 10, 1920.

Application filed March 1, 1917. Serial No. 151,811.

To all whom it may concern:

Be it known that I, JOSEPH H. COPE, a citizen of the United States, residing at the city and county of Denver and State of Colorado, have invented certain new and useful Improvements in Spring-Pullbacks for Haystackers; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means for automatically initiating the return movement of the stacker head in haystackers, my object being to provide a simple and economical construction which shall efficiently perform the aforesaid function. In haystackers of the class to which this invention applies, the stacker head which carries the load is secured to bars which are pivotally connected with the stationary part of the frame and during the lifting of a quantity of hay or other material, the head is raised and at the time it unloads, these bars which carry the head have usually passed the vertical position in the direction of the lifting travel and consequently some means must be employed to reverse the movement of the head until it has passed the vertical or dead center position in the opposite direction, in order that it may automatically return to its lowermost or normal position. Heretofore various constructions have been employed for accomplishing this function. My present improvement has an important advantage due to the fact that it is exceedingly simple in construction and consequently very inexpensive. It is particularly adapted for use in connection with so-called extension arm stackers of the construction set forth in my former Letters Patent No. 701,257 dated May 27, 1902. In the construction of the last named patent, links which are pivotally connected with the stationary frame work of the stacker, are so arranged that they act upon the bars which carry the stacker head, to extend the head as the latter is elevated. In the drawing I have illustrated the specific construction disclosed in my former Patent No. 924,534

dated June 8, 1909, the said links being arranged to slide upon the bars carrying the stacker head until they reach a stop as a bolt which is adjustable on the bars to occupy any desired position, according to the degree of extension required, the latter depending upon the height of the stack. In starting a stack no extension of the stack head is required, but the necessity for the spring pull-back is the same whether the head is extended or not.

In my improvement the extremities of the links which slidably engage the pivoted bars of the stacker head, serve to distend or stretch spiral springs, whereby the said bars and the stacker head are acted upon due to the recoil of the springs, to impart the necessary reverse movement after the stacker head has reached its limit of movement for elevating and discharging the load.

Having briefly outlined my improvement, I will proceed to describe the same in detail, reference being made to the accompanying drawing in which is illustrated an embodiment thereof. In this drawing—

Figure 1 is a side elevation of a hay-stacker equipped with my improvement.

Fig. 2 is a fragmentary detail view showing one pair of pull-back springs attached to the structure. This is a view looking in the direction of arrow 2 Fig. 1 with the parts shown on a larger scale.

Fig. 3 is a view of these springs distended or placed under tension as is their condition when the stacker head has completed its travel in the direction for lifting and discharging its load. This is a view looking in the direction of arrow 3, Fig. 4, the parts being shown on a larger scale.

Fig. 4 is a view of the structure shown in Fig. 1 when in the elevated position and with the pull-back springs distended or placed under tension.

Fig. 5 is a fragmentary side elevation of a stacker equipped with a slightly modified form of construction.

Fig. 6 is a fragmentary side view illustrating another form of construction.

The same reference characters indicate the same parts in all the views.

Referring first to Figs. 1 to 4 inclusive, let the numeral 5 designate the relatively stationary bottom frame bars of a haystacker, and 6 the upright bars at the rear extrem-

ity of the frame and which are rigidly secured thereto as shown at 7 and 8, the rear portion of the bars 5 being reinforced as shown at 10. To the part 10 of the frame, lifting bars 9 are pivotally connected as shown at 12 and extend forwardly therefrom to a position underneath the rear part of the stacker head 13, the latter being rigidly secured to bars 14 which are arranged above the bars 9 and are free to slide thereon for the purpose of projecting the stacker head outwardly during the lifting movement. In order to extend the stacker head, links 15 are employed one extremity of each being pivotally connected as shown at 16 to a bracket 17 which is secured to the upright frame bar 6 and at the upper extremity of the latter.

The opposite extremity of each of the links 15 is equipped with a member 18 having a projection 19 adapted to engage a stop mounted on the bar 14 when it is desired to extend the said bar together with the head 13 during the stacking operation. The frame bars 14 are each provided with a number of perforations 20 in any one of which a bolt or pin may be inserted which will lie in the path of the projection 19 during the lifting movement of the stacker head, the position of the stop bolt or pin depending upon the degree of extension which it is desired to impart to the stacker head during the lifting movement.

My present improvement as disclosed in Figs. 1 to 4, consists specifically of two spiral springs 21 each of which is connected at one extremity as shown at 22 with a pin 23 which is secured to the adjacent bar 9, the opposite extremity of each spring being connected as shown at 24 with a pin 25 which is mounted on a bracket 26, the latter having depending lugs 27, the said bracket being arranged to slide freely on the bar 14. Hence, during the lifting movement of the stacker head the projections 19 of the links 15 will travel along the bars 14 until these projections 19 engage a stop pin or bolt mounted in a perforation 20 of the corresponding bar 14, whereby the bars 14 will be projected outwardly on the bars 9 whereby the stacker head will be extended. During this outward or extended movement of the bars 14 on the bars 9, the extremity 28 of each link 15 will engage the bracket 26 with which the springs 21 are connected, and cause the said brackets to move along the adjacent surfaces of the bars 14, whereby the springs 21 are distended or placed under tension by the time the stacker head reaches its limit of lifting and rearward travel as illustrated in Fig. 4. As soon as the power acting to elevate the stacker head through the medium of the lifting bars 9 and the bars 14 connected with said head, ceases to act, the recoil of the springs 21, will cause the bars 14 and the head 13 to move in the reverse direc-

tion until they have passed the vertical or dead center position, after which they will return by gravity to their lower-most or normal position.

Assuming that it is not desired to elevate the stacker head, as when beginning the stack and when the stack is low, the stop pins or bolts will not be employed in the perforations 20 of the bars 14 of the stacker head and consequently the extremities 28 of the links 15 will move outwardly on the bars 14 until they engage the brackets 26, and the springs 21 will be distended or stretched during the remainder of the lifting movement. It will thus be understood that the springs 21 will be placed under tension by the time the stacker head has reached its limit of travel for elevating and discharging the load, to such an extent that their recoil action will impart the reverse movement to the head and bars 14 until they have passed the vertical or dead center position.

In the form of construction shown in Fig. 5, the springs 29 are employed, being substantially of the same construction as the springs 21. However, these springs 29 are connected as shown at 30 with the members 18 of the links 15, whereby the springs are carried along with the links during the upward movement of the lifting frame bars 9 and the bars 14 arranged in slidable relation therewith. The free extremities, however, of the springs 29 are equipped with hooks 31 which are adapted to engage stop pins 32 carried by the pivoted lifting bars 9, whereby the hooked extremities of the springs are prevented from further movement, thus distending the springs 29 during the remainder of the lifting travel of the stacker head, it being assumed that the projections 19 of the members 18 are in engagement with stop pins 33 which have been applied to the bars 14.

It should be explained that the stretching or distending action of the springs 21 or 29 as the case may be, should not commence until the lifting travel of the stacker head is nearly completed, since the springs will be quickly distended or stretched sufficiently to perform their function of imparting sufficient reverse movement to the stacker head and the bars 14 to cause these elements to move in the reverse direction beyond the vertical or dead center position after which they together with the arms 9 return by gravity to their lower-most position.

As illustrated in Fig. 5, the normally free extremities of the springs 29 are supported in position to engage the stop pins 32, by weak springs 34 which are connected as shown at 35 with the links 15, their opposite extremities being connected with the hooks 31 of the springs 29. It will be understood that any suitable means may be employed for holding the hooked extremities

of the springs 29 in position to engage the stop pins 32.

In the form of construction shown in Fig. 6, it is assumed that the bars 14 of the stacker head are caused to slide upon the bars 9 without the interposition of links 15, since other means for extending the stacker head and the arms 14 may be employed, that is means other than the links 15. In the form of construction shown in Fig. 6, pins 36 may be inserted in openings 37 formed in the bars 14, in order to catch the slideable brackets 26 and distend the springs 21, just before the lifting structure reaches its limit of lifting or rearward travel whereby the springs 21 are sufficiently distended to enable their recoil action to impart the necessary rearward movement to the pivoted lifting structure, as heretofore explained. In Fig. 6 two positions are illustrated, one in full lines and the other in dotted lines, the latter being the position of the parts when the springs are distended or placed under tension for the performance of the pull-back function.

Attention is called to the fact that in the forms of construction shown in both Fig. 1 and Fig. 5, the springs 21 or 29 as the case may be, are placed under tension by virtue of the movement of the links 15 during the lifting operation, whether or not the arms 14 carrying the stacker head are extended by the action of the links, since the stretching or distending of the springs is due to the movement of the links and does not necessarily involve the movement of the arms 14 and the stacker head. On the contrary in the form of construction shown in Fig. 6, it is necessary that the arms 14 have relative longitudinal movement independently of the arms 9 in order that the springs 21 may be distended or placed under tension. Hence this last named form of construction provides for a case in which links 15 or other similar elements are not employed for extending the stacker head.

Having thus described my invention, what I claim is:

1. A haystacker having a frame member and a structure pivotally mounted to oscillate, the latter comprising a pivoted member and a second member mounted upon and adapted to travel in a direction lengthwise of the first named member, a spring connected with one of said members, and a link slidably connected with one of said members and adapted to place the spring under tension during the lifting operation.

2. A stacker comprising a structure pivoted to oscillate, said structure including two members, one being pivoted and the other being movable in a direction lengthwise of the first, and a spring extending between the two members, said spring being fixed at one extremity to one member while

its other extremity is relatively movable a predetermined distance on the other member, and means having a relatively stationary portion and a relatively movable portion for engaging and checking the travel of the movable extremity of the spring on the adjacent member to cause it to move with the adjacent member whereby the spring is distended.

3. A haystacker comprising a pivoted lifting frame, a second frame carrying the stacker head and movable independently of the lifting frame and longitudinally of the latter, a spring secured to the lifting frame at one extremity, its opposite extremity being movable in relation to the second member, and means of checking the travel of the last named extremity with relation to the second member during the lifting movement of the stacker head whereby the spring is placed under tension for the purpose set forth.

4. A haystacker comprising a pivoted lifting frame, a second frame carrying the stacker head and movable independently of the lifting frame and longitudinally of the latter, a spring secured to the lifting frame at one extremity while its opposite extremity is connected with the second frame, and means for extending the second frame relatively to the lifting frame.

5. A stacker including a pivoted lifting frame, a stacker head frame movable on the lifting frame, a spring member having one extremity secured to the lifting frame while its opposite extremity is movable with relation to the stacker head frame, and a link member pivoted above the stacker head frame when at its lowest limit of movement, the opposite extremity of the link member being slideable on the stacker head frame and adapted to engage the extremity of the spring member which is normally movable on the stacker head frame, and stop said movement during a predetermined period of the lifting travel of the two frame members.

6. A haystacker including a lifting frame and a stacker head frame movable longitudinally of the lifting frame, a spring member having one extremity secured to the lifting frame while its opposite extremity is connected with a bracket slideable on the stacker head frame, and a link member pivotally connected above the said frames when at their lowest limit of movement, the opposite extremity of the said link member being movable in relation to the said frames during the lifting movement of the stacker, and arranged to engage the bracket of the spring member whereby the latter is placed under tension for the purpose set forth.

7. A haystacker having a structure comprising two lifting members pivotally mounted to oscillate one being movable on the other, a link pivoted at one extremity

while its opposite extremity is slidable on the said structure, and a spring member connected with the said structure and arranged to be placed under tension by the link during lifting movement of the latter.

8. A stacker having a structure including two members pivotally mounted to oscillate one being movable longitudinally of the other, a spring pull-back mounted on the said structure, and a link pivoted at one extremity while its opposite extremity is arranged to act on said pull-back to place the same under tension during the lifting operation.

15 9. A haystacker having a structure pivotally mounted to oscillate and composed of a pivoted member, and a second member having travel in a direction lengthwise of the first named member, a spring pull-back mounted on one of said members, and means on the device adapted to place the pull-back under tension during the lifting movement.

10. A haystacker having a structure pivotally mounted to oscillate and composed of two members, one having longitudinal travel on the other, a spring pull-back and means on the device adapted to place the pull-back under tension during the lifting movement of said structure.

30 11. A stacker including a frame member, a movable lifting member, connected with the frame member, a link member slidably connected with one of said members, and a spring pull-back on one of said members adapted to be placed under tension through

the relative movement of said members during the lifting operation.

12. A stacker having a lifting member pivotally mounted to oscillate vertically, a link member pivoted at one end while its opposite end is movable longitudinally of the lifting member, and a spring pull-back connection on one of said members and adapted to be placed under tension through the medium of the link member during the lifting movement.

13. A stacker having a lifting member, a link member pivoted at one end while its opposite end is movable longitudinally of the lifting member, and a spring pull-back connected to one of said members and mounted for engagement with the other member to be placed under tension through the medium of the link member during the lifting movement.

14. A stacker having a lifting structure comprising a pivoted member and a member longitudinally slidable on said pivoted member, a link pivotally mounted at one end and slidably mounted at the other end, and a spring pull-back connection between said two members adapted to be placed under tension through the medium of the link during the lifting movement.

In testimony whereof I affix my signature, 65
in presence of two witnesses.
